UNITED STATES PATENT OFFICE.

JAMES P. ORR, OF PITTSBURG, AND THEODORE F. GALVIN, OF MCKEESPORT, PENNSYLVANIA; SAID GALVIN ASSIGNOR TO GEO. H. FUGH, OF PITTSBURG, PENNSYLVANIA.

ELECTRICAL SIGNAL-BELL FOR STREET-CARS.

SPECIFICATION forming part of Letters Patent No. 596,085, dated December 28, 1897.

Application filed August 3, 1896. Serial No. 601,474. (No model.)

To all whom it may concern:

Be it known that we, JAMES P. ORR, residing at Pittsburg, and THEODORE F. GALVIN, residing at McKeesport, in the county of Allegheny and State of Pennsylvania, citizens of the United States, have invented a new and useful Electrical Signal-Bell for Street-Cars, of which the following is a specification.

Our invention relates to improvements in signal-bells where a definite number of distinct strokes of bell is desired; and the objects of our improvement are, first, to provide an alarm or danger-signal that will give automatically the desired number of strokes; second, to afford facilities for the motorman to give the danger-signal promptly while both hands are engaged with the levers of the motor and the brake, respectively. We attain these objects by the mechanism illustrated in the accompanying drawings, in which—

Figure 1 is a plan view of entire machine with bell removed. Fig. 2 is a plan view of circuit-breaker and a diagrammatic view illustrating the circuit in our invention. Fig. 3 is a sectional side elevation of entire machine on a central longitudinal line *y x*.

Similar letters refer to similar parts throughout the several views.

At A, Fig. 1, is shown a pair of coils with cores and vibrating armature in the usual manner and mounted on a metallic plate B, having an arched bell-post B², which is provided with a screw and nut B³, adapted to the double purpose of holding bell G, Fig. 3, firmly in position and providing a pivotal mounting for ratchet-wheel D. Armature C is provided with lever C², to which is pivotally connected pawl C³, adapted to engage ratchet-wheel D, producing rotary motion by reciprocating lever C². Ratchet-wheel D is provided with rollers D', mounted near its periphery, the number of rollers being equal to the number of strokes required on bell. Sleeve E is provided with a short arm and ball or clapper E⁴ and a curved arm E³, medially mounted and adapted to engage rollers D' with its curved end and hub D² with its straight end. Sleeve E is mounted on insulated pin E² and held in its normal position

at rest by a spiral spring, which is also insulated from plate B.

Hub D², Fig. 2, has inserted in its peripheral surface an insulating-block D⁴, adapted to receive the straight end of E³ when its curved end is released from D', Fig. 1, as shown by dotted lines, thus opening the circuit. As E³ is the only conductor between pin E² and hub D², it is apparent that if pin E² and hub D² are connected temporarily, while insulator D⁴ is being rotated from contact with E³ or until D' engages the opposite end of E³, the break will be closed and the current will be conducted through D or directly to hub alternately as the opposite ends of E³ are engaged until one revolution of wheel D is completed and E³ engages D⁴. Wheel D not being insulated from plate B or standard-supporting armature C current is conducted by wire or plate B to armature-spring, making an interrupted connection with adjusting thumb-screw mounted on an insulated standard. Armature-spring and thumb-screw being in contact (at rest) when the circuit is closed cores A A are magnetized and armature C drawn in contact with cores, separating spring from thumb-screw, breaking the circuit, demagnetizing the cores, and allowing armature to return and close the circuit and again magnetizing cores A A, thus automatically producing reciprocal motion in armature, the electromagnetic force being applied to rotate wheel D through lever C² and pawl C³.

To set wheel D in motion to give the signal, it is only necessary to connect pin E with any part of plate B temporarily. This is preferably done by circuit-closer F², which is placed in a convenient position in floor of car-platform, as shown in diagram, and electrically connected with E² and D². In Fig. 3, F² is shown as mounted on base-supporting plate B.

In Fig. 1 the circuit shown is as when the motor is in motion, "short-circuiting" F² and connections, which are omitted from this figure to avoid confusion. The direction of current is as shown by representation of battery in diagram; but to amplify in the tracing of current and opening and closing circuit let it be observed that standard-supporting spring

and armature C, also arched bell-post B², supporting bell G and wheel D, are all electrically connected with plate B, but pin E and standard having adjusting thumb-screw adapted to make an interrupted electrical connection with armature-spring C are the only two parts insulated from plate B, as shown in Fig. 3. Current from battery or dynamo is conducted to insulated standard, which is connected with armature-spring by thumb-screw and forms an automatic current-breaker, closing circuit through frame or other conductor with hub D², which is connected with pin E² by lever E³, which is alternately in contact with D² or one of rollers D' while wheel D is in motion, but in contact with insulator D⁴ when at rest. Current from pin E² is conducted by insulated wire to helices A, thence to battery, or to earth if current from dynamo is used. F² is a lever pivotally mounted at one end and perforated at the other end adapted to receive a pull cord or wire if located in roof of car-platform, or thumb-key if located on motor-handle, or a pedal if located in floor of car-platform and adapted to engage contact-plate. Said lever and said contact-plate are each connected by wire with hub D² and pin E², respectively. Now if motion is arrested by a break in the circuit between these two points D² and E² it follows that if these points are connected motion will be resumed. Hence the working circuit and the starting-circuit is the same, except a slight difference in length, limited

only by the location of F², which has been 35 described. Armature-spring C is rigidly mounted on a suitable standard and is firmly connected to armature which has an extending lever C² and pawl C³, adapted to engage ratchet-wheel D, and held in contact with the 40 latter by a suitable spring forming an electrical as well as a mechanical connection between C and D.

Having thus fully described our invention, we claim and desire to secure by Letters Patent—

1. In an electric signal-bell, the combination of a bell-clapper and its arm, a ratchet-wheel having thereon antifriction-rollers adapted to engage the bell-clapper arm and 50 an automatic circuit-opener with a lever C attached to a vibrating armature, a pawl pivotally mounted on the end of the armature which is adapted to engage and propel the wheel D, substantially as described. 55

2. In an electric signal-bell, the combination of a bell-clapper and its arm, a ratchet-wheel having thereon antifriction-rollers adapted to engage the bell-clapper arm, and an automatic circuit-opener with sleeve E, 60 mounted on insulated pin which is electrically connected with B by circuit-closer F² for the purpose specified.

JAS. P. ORR.
THED. F. GALVIN.
